PROJECTILE

William J. Landen, Arlington, Va.

Application January 16, 1940, Serial No. 314,100

3 Claims. (Cl. 102—56)

(Granted under the act of March 3, 1883, as amended April 30, 1928; 370 O. G. 757)

The invention described herein may be manufactured and used by or for the Government for governmental purposes, without the payment to me of any royalty thereon.

The subject of this invention is a projectile.

The purpose of the invention is to provide an explosive projectile which may be inexpensively and easily fabricated and which is arranged to receive a simple firing mechanism.

The specific nature of the invention as well as other objects and advantages thereof will clearly appear from a description of a preferred embodiment as shown in the accompanying drawing in which:

Fig. 1 is a longitudinal sectional view of a projectile constructed in accordance with the invention;

Fig. 2 is a similar fragmentary view illustrating a modification.

Referring to the drawing by characters of reference the projectile comprises a body 5, a neck 6 and a head 7. The body part 5, which is preferably of gilding metal so as to be capable of being engraved by the rifling of a gun barrel, is formed with a closed base 8 and with a chamber 9 opening into the front face of the body and adapted to conveniently receive an explosive charge 10. The body is formed with a reduced cylindrical front portion 11 providing annular shoulders 12 and 13.

The head part 7, which is preferably of a metal such as aluminum having a low shear strength, has an ogival front end 14 and a reduced cylindrical rear end 15 providing an annular shoulder 16. The rear end 15 is formed with one or more rearwardly extending projections 17—17 which are to serve as firing pins.

The neck part 6 which is preferably of a more rigid metal such as brass, is formed with front and rear cylindrical recesses respectively 18 and 19. The front recess 18 receives the rear end 15 of the head with a force fit, the shoulder 16 of the head seating on the front end of the neck and determining the relative longitudinal position of the firing pin projections 17. The rear recess 19 receives the front portion 11 of the body with a force fit and the annular shoulders 12 and 13 respectively seat on the rear end of the neck and on the floor 20 of the recess 19. When thus assembled the neck constitutes a coupling between the head and the body and it is forwardly tapered to gradually merge the contours of the body and the ogival end 14 of the head.

The recesses 18 and 19 of the neck are connected by a passage or recess 21 whose diameter approximates the diameter of the chamber 9 in the body and is less than the diameter of the front recess 18 to provide an annular counterbore shoulder 22. A commercially obtainable percussion primer, for example a blank, cal. .22, is 60

housed in the passage 21 and consists of a cup 23 having a flange 24 and carrying a priming charge 25. The flange 24 of the cup is seated on the annular shoulder 22 in position to be struck by the projections 17 of the head.

When the projectile strikes an object the annular shoulder 16 of the head being seated on a rigid base is sheared or deformed and the head moves rearwardly relatively to the neck, the projections 17 striking the primer and serving as firing pins to ignite the priming charge and thereby set off the explosive charge. The sensitivity of the firing mechanism on impact will be dependent on the character, quality or strength of the metal at the shoulder 16. The metal on the line of shear or deformation may be strong or weak as occasion may require.

In the modification shown in Fig. 2 the major portion of the neck part 6 of Fig. 1 is combined with the body 5a and a washer 6a of a rigid metal to facilitate shearing forms a seat for the head 7a.

I claim:

1. A projectile comprising a body part having a reduced front end, an explosive charge in the body, a neck part force fitted on the reduced front end of the body, said neck part having a counterbored recess from its front end to the front end of the body and providing an annular shoulder, a primer including a flanged cup inserted in the rear part of the counterbored recess with its flange seated on the annular shoulder thereof, an ogival head part having a reduced portion force fitted in the front part of the counterbored recess in front of the primer and having a shearable shoulder seated on the front face of the neck part.

2. A projectile comprising a body part having a reduced front end, an explosive charge in the body, a neck part on the reduced front end of the body, said neck part having a counterbored recess from its front end to the front end of the body and providing an annular shoulder, a primer including a flanged cup inserted in the rear part of the counterbored recess with its flange seated on the annular shoulder thereof, an ogival head part having a reduced portion in the front part of the counterbored recess in front of the primer and having a shearable shoulder seated on the front face of the neck part.

3. A projectile comprising a body part of a relatively soft metal adapted to engage the rifling of a gun barrel, an explosive charge in the body part, a neck part of a more rigid metal assembled to the body part, a primer in said neck part, and a head of a metal having a low shear strength assembled to the neck part and adapted to serve as a firing pin on impact.

WILLIAM J. LANDEN,
